UNITED STATES PATENT OFFICE

JAMES DORST AND PHILIP BACHHUBER, OF MAYVILLE, WISCONSIN

FREEWHEELING ATTACHMENT

Application filed May 2, 1931. Serial No. 534,628.

This invention relates to free wheeling devices and more particularly to an attachment which may be used for this purpose on any conventional motor vehicle.

5 An object of this invention is to provide a free wheeling attachment which may be mounted on any conventional motor vehicle without disturbing the present parts of the vehicle.

10 Another object of this invention is to provide a free wheeling attachment which operates to disengage the clutch simultaneously with the release of the carburetor throttle.

15 Another object of this invention is to provide an automatic free wheeling device of this kind which may be suitably adjusted to free wheel at any desired speed and which, in addition thereto, will slowly release the clutch so as to prevent stalling of the engine.

20 A further object of this invention is to provide a device of this kind which is so constructed as to eliminate the necessity of touching the clutch during the operation of shifting gears.

25 The above and various other objects and advantages of this invention will in part be described in and in part be understood from the following detailed description of the present preferred embodiment, the same being illustrated in the accompanying drawings, wherein:—

30 Figure 1 is a detail side elevation of a device constructed according to the preferred embodiment of this invention mounted on a motor vehicle;

35 Figure 2 is a longitudinal section partly in detail of the suction valve showing the valve in operative position;

40 Figure 3 is a similar view showing the valve in inoperative position;

45 Figure 4 is an enlarged fragmentary top plan view showing the air inlet for the suction valve;

50 Figure 5 is a longitudinal sectional view partly in detail of the clutch operating means;

55 Figure 6 is a detail top plan view of the clutch operating member, and

Figure 7 is a fragmentary side elevation of a modified form of connecting this invention with the throttle.

Referring to the drawings wherein like numerals of reference designate corresponding parts through the several views, the numeral 10 designates generally a motor vehicle engine which is provided with the conventional intake manifold 11 and a transmission having a clutch pedal 12. The motor vehicle is also provided with the conventional steering column 13 which extends inwardly of the vehicle from the engine compartment.

60 In motor vehicles at present available, in order to shift gears, it is necessary to operate the clutch pedal 12 by means of the foot during each shifting operation or when it is desired to free wheel, or in other words, to let the vehicle coast while the engine 10 is running at what is commonly termed idling speed.

65 In order to effect free wheeling of conventional vehicles without disturbing the present parts of the vehicle, I have provided an attachment which is connected at one point to the throttle 14 which is operated by the foot of the driver and connected to the carburetor of the vehicle. A cylinder generally designated as 15 is mounted on the manifold 11 and provided with a port 16 which is connected to the intake manifold. One end of the cylinder 15 is open and a piston or valve member 17 is slidably mounted within the cylinder 15. The cylinder 15 is also provided with a second port 18 and an enlarged chamber 19 disposed intermediate the ends of the cylinder 15 and with which the second port 18 communicates.

70 An air inlet port 20 is also provided in the cylinder 15 and a threaded regulating screw 21 is threadably mounted in the cylinder 15, and is adapted to partially close the inlet 20 so as to regulate the quantity of air passing through this inlet. The piston 17 is provided intermediate the ends thereof with an elongated slot 22 which, when the piston 17 is moved inwardly, establishes communication between the air inlet port 20 and

- the outlet port 18 and cuts off the suction of the suction port 16 from the port 18. One end of the piston 17 is connected to the throttle rod 14 by means of a link member 23 so that as the throttle 14 is moved inwardly under the pressure of the foot of the operator, the piston 17 is simultaneously moved inwardly and conversely when the throttle rod 14 is moved outwardly under the action of the convention spring mechanism, the piston 17 is moved outwardly, cutting off the air inlet port 20 and establishing communication between the suction port 16 and the outlet port 18.
- 15 A clutch pedal operating member, generally designated as 24, is mounted on the steering column 13 by means of a bracket member designated 25, which is constructed in two parts having one part integral with the base portion 26 of the operating member 24, and the other part of the bracket 23 comprises a semi-cylindrical member 27 which clamps about the steering column 13 and is held into engagement therewith and 25 with the other portion of the bracket 25 by means of bolts 28 or the like.
- 20 The base or body portion of the operating member 24 is connected to the suction member or cylinder 15 by means of a pipe line 29. This base member 26 is of hollow construction and provided with an outstanding flange 30 upon which a diaphragm 31 of resilient or flexible construction is mounted by means of a securing ring 32 which is 30 fastened to the flange 30 by means of bolts 33 or the like. A pedal engaging lever, generally designated as 34, is rockably secured to the diaphragm 31 by means of a post 35 or the like which is pivotally secured to the 35 lever 34 intermediate the ends thereof, one end of the post 35 being secured to the diaphragm 31 at substantially the center thereof and reinforcing or protecting plates 36 are disposed on the opposite sides of the diaphragm 31 so as to prevent injury to the diaphragm upon movement inward and outward thereof under the action of the lever 34.
- 40 One end of the lever 34 is pivotally mounted on an upstanding post or support 37 which is mounted on the base portion 26 at a point substantially diametrically opposed from the bracket 25 and a stop member 38 is mounted on the base member 36, 45 and is adapted to limit the rocking movement of the lever 34. The opposite end of the lever 34 is provided with a hook or reverted portion 39 which loosely engages about the clutch pedal 12.
- 50 The diaphragm 34 may be constructed of any resilient or flexible material which is actuated by the suction of the motor 10 but which, at the same time, will return to its normal position in a relatively short time so 55 that when the piston 17 is moved inward-

ly, the air will pass through the air inlet port 20 and through the pipe line 29 so as to relieve the vacuum caused by the suction of the motor 10.

It will, of course, be understood that the lever 39 is also facilitated in its rocking movement to an inoperative position by means of the clutch pedal springs so that the action of the diaphragm 31 is facilitated by the the return of the clutch pedal.

In the operation of this device, when the vehicle is in motion and the throttle 14 is depressed, the plunger or piston 17 will be moved inwardly of the cylinder 15 under the action of the throttle rod 14 so as to permit the passage of air from the inlet port 20 through the outlet port 18 and the pipe line 29 into the base member 26 of the clutch operating member 24. In this position, the operating member 34 is in inoperative position and the clutch 12 is rocked rearwardly under the action of the conventional clutch operating springs (not shown).

When the foot is released from the throttle 14 and the throttle is moved rearwardly under the action of the conventional spring mechanism, the piston 17 is simultaneously moved rearwardly so as to establish communication with the suction port 16 and the outlet port 18. The suction caused by the idling action of the motor 10 will cause a partial vacuum in the base member 26 and the diaphragm 31 will be drawn inwardly, thereby coercively rocking the clutch operating lever 34 on the supporting member 27 and causing the free end thereof to rock the clutch pedal 12 forwardly into neutral or disengaged position. The clutch pedal 12 will be held in inoperative or disengaged position as long as the throttle 14 is not in idling position and as long as the motor 10 is operating. When the throttle 14 is pushed inwardly so as to speed up the motor 10, the plunger or piston 17 is forced inwardly so as to establish communication between the air inlet port 20 and the outlet port 18 whereby the vacuum within the base member 26 will be relieved so that the diaphragm 31 can expand or move outwardly, which will rock the clutch engaging lever 34 on the post 37 and release the clutch pedal 12 for rocking movement into operative position.

The free wheeling device herein described can readily be mounted on any conventional motor vehicle having an internal combustion engine and a manually operable clutch and transmission.

As shown in the modification of this invention in Figure 7, the connecting link 23' is connected at one end to the foot throttle 14 and is provided intermediate the ends thereof with an elongated slot or recess 40, and the throttle rod 41 is provided at the inner end thereof with a bifurcated member 42 which has a pin 43 disposed through

the bifurcated ends thereof, the pin 43 being disposed in the slot 40 of the valve link 23'. Through the use of this modification, the valve member 17 is moved initially and prior to the opening or closing of the throttle so that the engine will not be driven at an increased speed prior to the operation of the free wheeling attachment. The connecting links 23 and 23' are preferably mounted so that the hand throttle can be used for operating the motor independently of the free wheeling attachment.

It will be understood that in conventional throttle operating mechanisms, the hand throttle is operated independently of the foot throttle and in this manner, the free wheeling attachment which is connected to the foot throttle will be maintained in inoperative position during the time that the hand throttle is being used. Furthermore, by connecting the free wheeling valve member 17 to the link 23', as disclosed in the modification, the engine is not rotated at an excessive speed prior to the operation of the lever 34 which engages the clutch 12. In other words, the valve member 17 is moved into operative position for causing the suction of the motor to draw the diaphragm 31 inwardly and coercively rocking the clutch lever 34 prior to the movement of the throttle into idling position and conversely when it is desired to release the free wheeling device, the device is released prior to the speeding up of the engine. In this manner, the clutch pedal 12 will be released at the lowest or idling speed of the motor rather than a higher speed.

It is, of course, understood that various changes and modifications may be made in the details of construction and design of the above specifically described embodiment of this invention without departing from the spirit thereof, such changes and modifications being restricted only by the scope of the following claims.

What is claimed is:—

1. A free wheeling device of the character described, comprising the combination with a motor vehicle and an engine therefor, of a resilient diaphragm supported within the vehicle, lever means connecting the diaphragm with the clutch pedal for rocking of the pedal upon movement of the diaphragm, said diaphragm normally maintaining said lever means ineffective and suction means connecting the diaphragm and the vehicle engine whereby to move the diaphragm.

2. The combination with a motor vehicle and an engine therefor, of a casing supported within the vehicle, a resilient diaphragm carried by the casing, a rockable member engaging the diaphragm and the clutch pedal whereby to rock the pedal upon movement of the diaphragm, said dia-

phragm normally holding said member in inoperative position, a suction cylinder connected to the engine, a piston slideable in said cylinder, means connecting the piston with the throttle, and means connecting the cylinder with the casing whereby to provide a substantial vacuum within the casing and coercively draw the diaphragm inwardly of the casing for rocking movement of the rockable member. 75

3. A free wheeling device of the character described, comprising the combination with a motor vehicle engine, of a resilient diaphragm, a pedal operating lever rockably engaging the diaphragm and the pedal whereby to rock the pedal in operative position or inoperative position upon flexing of the diaphragm, said diaphragm normally holding said lever in inoperative position and automatically operated means for flexing the diaphragm simultaneously with the movement of the carburetor throttle. 85

4. A free wheeling device of the character described, comprising a flexible dia- 90 phragm, a rockable pedal operating member carried by the diaphragm and loosely engaging the clutch pedal of the vehicle, said diaphragm normally holding said member in inoperative position, automatically operat- 95 ed suction means for moving the diaphragm in one direction whereby to rock the pedal forwardly, said automatically operated means permitting the diaphragm to flex in another direction whereby to release the lever from the clutch pedal upon rendering 100 said suction means ineffective.

5. A free wheeling device of the character described, comprising the combination with a motor vehicle and an engine therefor, of a flexible member, means connecting the flexible member with the clutch pedal of the vehicle whereby to rock the clutch pedal upon flexing of the member, said flexible member normally holding said connecting means in inoperative position and automatically operated suction means engaging the engine and the member whereby to flex the member in one direction for rocking the clutch pedal into declutched position, said member returning to normal inactive position when said suction means is rendered inoperative and simultaneously swinging said connecting means in a direction to permit free return of the pedal to clutching position. 110

6. The combination with a motor vehicle and an engine therefor, of a casing, a dia- 115 phragm carried by the casing, a rock lever carried by the casing and engaging the dia- 120 phragm, said rock lever also loosely engag- 125 ing the clutch pedal whereby to rock the clutch pedal in one direction upon rocking of the lever, said flexible member normally holding said lever in inoperative position, means for automatically withdrawing air from the casing whereby to move the dia- 130

phragm and the lever inwardly toward the casing and release means whereby to permit the entrance of air into the casing for movement of the diaphragm in the other direction for releasing the lever from the clutch pedal.

7. The combination with a motor vehicle and an engine therefor, of a casing, means for supporting the casing from the steering column, a flexible diaphragm, means for securing the diaphragm to the casing whereby to close the casing, a clutch operating lever rockably supported by the casing and engaging the diaphragm for rocking of the lever

10 coactive with the flexing of the diaphragm, said diaphragm normally maintaining said lever in inoperative position, a hook secured to the lever and loosely disposed about the clutch pedal, and means engaging the engine

15 throttle and the casing whereby to withdraw the air from the casing upon release of the throttle, said means also including means for admitting air into the casing upon forward movement of the throttle, flexing of

20 the diaphragm in one direction rocking the lever and pedal engaged thereby, flexing of the diaphragm in the opposite direction swinging the lever in a direction to permit the pedal to freely rock into clutching position.

8. In a free wheeling device of the character described, a flexible member, means connecting the flexible member with a clutch pedal for rocking movement of the pedal

25 upon flexing of the member and means for automatically flexing the member upon movement of the carbureter throttle, said automatic means including a suction cylinder, a piston slidably mounted in the cylinder,

30 means connecting the cylinder with the carbureter throttle, said cylinder having a suction port and an outlet port connected to the member, said piston having an elongated slot therein disposed inwardly from

35 each end thereof whereby upon inward movement of the piston the suction from said suction port is cut off, said cylinder also having an air intake port, said piston upon cutting off the suction from said suction port

40 being adapted to establish communication between the air intake port and said outlet port whereby to permit the passage of air to said member for flexing thereof, said member normally maintaining said connecting

45 means in inoperative position.

9. The combination with a motor vehicle and an engine therefor, of a casing, means for supporting the casing from the vehicle steering column, a diaphragm, means for securing the diaphragm to the casing whereby to close the casing, a clutch operating lever rockably supported by the casing and engaging the diaphragm for rocking the lever coactively with the flexing of the diaphragm, a valve member, means connecting

the valve member to the casing, a link connecting the valve member with the foot throttle, said link having an elongated slot therein, and a carbureter link having one end thereof disposed in said slot and the opposite end connected to the carbureter whereby the valve member is moved into operative position prior to opening or closing of the throttle.

In testimony whereof we hereunto affix our signatures.

JAMES DORST.
PHILIP BACHHUBER.
